United States Patent Office

Des. 183,514

Patented Sept. 16, 1958

183,514

GAME BOARD

Philip Glickman, Los Angeles, Calif.

Application September 3, 1957, Serial No. 47,583

Term of patent 14 years

(Cl. D34—5)

Fig. 1.

Fig. 2.

Fig. 1 is a top plan view of a game board, showing my new design; and

Fig. 2 is a vertical sectional view taken on the line 2—2 of Fig. 1.

The plan view represents a complete game board.

I claim:

The ornamental design for a game board, as shown and described.
